RAILWAY PASSENGER CAR

Albert G. Dean, Narberth, Pa.

Application March 19, 1956, Serial No. 40,661

Term of patent 14 years

(Cl. D66—1)

Fig. 1 is a side elevation of a railway passenger car embodying my new design;

Fig. 2 is a section of the skin on the line 2—2 of Fig. 1;

Fig. 3 is a section of the skin on the line 3—3 of Fig. 1;

Fig. 4 is a partial top plan view at one end of the car; and

Fig. 5 is an end elevation.

The essential features of my design reside in those portions shown in full lines in the drawing.

I claim:

The ornamental design for a railway passenger car, substantially as shown and described.
